UNITED STATES PATENT OFFICE

2,224,882

UMBRELLA

Herbert G. Peck, Miami, Fla.

Application August 1, 1939, Serial No. 287,837

12 Claims. (Cl. 135—2)

This invention relates to umbrellas and more particularly to a relatively large or giant size umbrella.

An object of this invention is to provide a large 5 size or giant umbrella which is adapted to be fixed to a suitable support, the standard or stick of the umbrella being in an upright position, and the cover including the ribs being of a collapsible construction.

Another object of this invention is to provide an 10 umbrella of this type with means whereby the weight of the extensible portions thereof is counter-balanced so that the umbrella may be readily shifted to an extended position without undue effort.

A further object of this invention is to provide 15 a giant umbrella of this type which is so constructed that the cover may be made to revolve so that the cover and/or valance may be provided with indicia for advertising or other purposes.

A still further object of this invention is to provide 20 an umbrella of this type which is so constructed that if desired the umbrella may be tilted and maintained in its tilted position.

A further object of this invention is to provide 25 in an umbrella of this kind, an improved means for securing the cover to the ribs so that the cover, if desired, may be made in segments 30 or sectors.

A further object of this invention is to provide, 35 in an umbrella of this type, an improved means for providing a sloping top so that the umbrella will readily shed water, and to provide an ornamental shape to the umbrella which is not entirely dependent upon the shape of the ribs.

A further object of this invention is to provide, 40 in an umbrella of this type, means for securing a single piece or stitched cover to the ribs.

A further object of this invention is to provide 45 a giant umbrella and improved means for raising or collapsing the umbrella.

To the above ends essentially and to others which may hereinafter appear, the invention 50 consists of the novel construction, combination, and arrangement of parts as will be more specifically referred to and illustrated in the accompanying drawings wherein is shown an embodiment of the invention, but it is to be understood 55 that changes, variations and modifications may be resorted to which fall within the scope of the invention, as claimed.

Figure 1 is a vertical section, partly in elevation, of a giant or large size umbrella, constructed 55 according to an embodiment of this invention;

Figure 2 is a fragmentary perspective view of a portion of the umbrella;

Figure 3 is a fragmentary vertical section of this invention;

Figure 4 is a fragmentary sectional view taken 5 on the line 4—4 of Figure 5;

Figure 5 is a fragmentary sectional view taken 10 on the line 5—5 of Figure 4;

Figure 6 is a fragmentary perspective view of the rib embracing structure embodied in Figure 1.

Referring to the drawings, numeral 15 designates generally a stem or standard which, in the present instance, is of tubular construction. The stem 15 is mounted in upright position on a base 15 plate 16, having a vertically disposed stud 17 which extends interiorly of the lower end of the stem 15, and which may be secured therein by set screws 18 or the like.

The cover 56 comprises a flexible body formed 20 of a plurality of segments which are adapted to be stitched or otherwise secured together and the cover 56, at the center or upper portion thereof, is preferably disposed above the inner ends of the ribs or bows 29. The cover 56 is provided in the 25 axeo center thereof with substantially conical reinforcing members 58 and 59 which engage on opposite sides of the cover 56 and are clamped tightly against the cover by means of fastening members 60. The upper end of the spring 54 30 bears against the reduced upper portion of the reinforcing member 58 and provides a yieldable connection or coupling for the central portion of the cover which is adapted to raise the central portion of the cover 56 in substantially conical 35 configuration, as shown in Figures 1 and 3.

The spring 54 will provide a means whereby the central portion of the cover 56 will be maintained taut at all times in addition to forming an ornamental shape to the central portion of the 40 cover. In addition to the foregoing the spring 56 forms a means whereby, when the umbrella is collapsed the cover 56 will not be placed under any undue strain as would be the case if the cover 56 is tightly secured to the upper portion 45 of the stem 15, or sleeve 23.

The cover 56 is provided, as shown in Figure 2, with a plurality of radially arranged rib receiving pockets 61 which comprise a pair of wall members 62 and 63 which are stitched, as by 50 stitching 64 to the under-side of the cover 56. These wall members 62 and 63 are provided with a plurality of spaced apart grommets 65 and a lacing 66 is threaded through the grommets 65 so as to removably secure the cover 56 on the 55

ribs 29. The outer ends of the two wall members 62 and 63 are secured together, as at 67, so that the outer end of a rib 29 may abut against the closed end 67 of the pocket 61 and thus stretch 5 the cover 56 longitudinally of a rib 29. The cover 56, at its outer edge, is provided with a valance 68 and is also provided with an annular flap or extension 69 which is positioned interiorly of the upper end of the valance 68. The 10 flap 69 is provided with a beading 70 and with a plurality of spaced apart grommets 71 so that depending walls, or the like may be detachably secured to the annular flap 69. In order to provide a means whereby the umbrella is held 15 against rotation, I have provided a flexible member 72 which is fixed, as at 73, to the stem 15, below the cap 21, and is secured by means of a clamping member 74. The opposite ends of the flexible member 72 are adapted to hold the umbrella against rotation by reason of the fact that one portion of the flexible member 72 extends 20 from the stem 15, from a point diametrically opposite from the other portion thereof, so that any tendency of the cover and ribs to rotate 25 relative to the stem 15 will cause the torque member 72 to wind upon the stem 15 irrespective of the direction of rotation. In this manner the ribs 29 and the securing means in the form of the pivot pins 28 will not be subjected to any 30 undue strain caused by partial rotation of the cover 56.

Referring to Figure 3, there is disclosed a stem 15 which is secured at its lower end to a stud 17 carried by a base plate 16. The stem 35 15 comprises a lower tubular member 75 and an upper tubular member 76. The upper tubular member 76 is rotatably mounted about a reduced extension 77, which is secured as a 78 to the upper portion of the lower member 75. A cap 40 member 21 is secured by fastening members 45 to the upper end of the rotatable member 76 and the cap member 21 comprises a lower sleeve 22 having radial arms 24. A top plate 44, having radial arms 25 is secured by fastening members 45 45 26 to the lower sleeve 22, the fastening members 26 extending through the arms 25 and 24.

A shaft 79 is fixed to the cap plate 44 in the center thereof and extends vertically through the stem 15. The lower end of the shaft 79 is journalled through the stud 17 and is provided with a bevelled gear 80 with which a driving gear 81 meshes. The driving gear 81 is connected to a shaft 82 carried by a motor or power member 83. The base plate 16 is secured to a housing 55 84 which, in the present instance, is adapted to be embedded in the ground or secured to a suitable support, the plate 16 being secured to the housing 84 by means of bolts 85. The housing 84 is preferably embedded in concrete 19. The shaft 79 extends upwardly above the cap 21, as at 86, and the cover 56 is provided with a conical reinforcing means 58 engaging about the shaft extension 86. A spring 54 engages in an annular groove 53 formed in the top plate 44 and bears 60 against the reinforcing cap 58 for the cover 56. The outer cap 58 is tightly held to the cover 56 by means of an inner frustro-conical ring 59 and fastening members 60.

The structure shown in Figure 3 includes ribs 70 29 and a sleeve or slide 32. Bracing members 38 extend from the sleeve 32 and are connected to the truss members 30. The truss members 30 include a brace 31 connected between a truss member 30 and a rib 29.

75 The lower end of the upper stem or sleeve

member 76 is rotatable on the upper end of the lower member 75, and, if desired, suitable anti-friction bearings may be interposed between the lower end of the upper member 76 and the lower member 75.

In Figures 4 and 5 there is disclosed a means whereby the umbrella structure may be tilted out of the vertical. A stem member 15c is provided at its lower end with a pair of spaced apart arms 91 and a boss 92 is carried by each 10 arm 91. A nut member 93 is mounted between the arms 91 adjacent the lower ends thereof, being pivotally mounted on pivot members 94 engaging through the arms 91. A tilting screw 95 in the form of a threaded shaft is threaded 15 through the nut 93 and is rotatably carried by a vertical wall 96 which is provided on the upper side of a gear member 97. A pair of spaced apart vertical brackets or arms 98 are fixed to the gear 97 and a shaft 82c is journalled through the bearing members or arms 98 and through the arms 91. A shaft 79c extends through the stem 15c and is provided at its lower end with a gear 80c meshing with a gear 81c carried by the drive shaft 82c and positioned between the arms 91. 20 The gear member 97 is rotatably mounted on a base 99, and is disposed within an annular clamping member comprising a vertical wall 100, having a base flange 101. An inwardly projecting flange 102 extends from the upper end of the 25 cylindrical member 100 and engages over the top of the gear 97. A pinion 103 meshes with the gear 97 and is secured to a crank 104, the lower end of the crank 104 being journalled in the base 99. With a construction of this kind the 30 umbrella mounted on the stem 15a may be manually rotated by rotation of the pinion 103. If desired a suitable power means may be substituted for the crank 104.

In the use and operation of this umbrella the 35 stem 15 is adapted to be anchored to a suitable support by means of the anchoring bolts 20. If desired the anchoring bolts 20 may engage in a concrete base or may be secured to any other suitable support. When the umbrella is in its 40 extended position the slide 32 is locked by means of locking members 51 so that the elevating member 41 will be relieved of supporting the umbrella in its extended position. The weight 47 will provide a means to at least partially counter-balance the weight of the cover and the ribs.

Where it is desired to have an umbrella of this structure rotate, the structure shown in Figure 3 may be used, or, if it is desired to tilt the umbrella at any suitable angle, the tilting structure shown in Figures 4 and 5 may be secured to the lower end of the stem. As shown in Figure 5 the shaft 95 is provided with collars 114 and 115 engaging on opposite sides of the wall 96. The outer end of the shaft 95 may have a crank engaged with a nut portion 116 formed on the outer end of the shaft 95. With a structure as shown in Figures 4 and 5, the cover may, if desired, be rotated through a drive shaft 82c and the shaft 79c. In addition to this the entire structure may be 55 rotated in its tilted position by means of the crank 104 or other suitable power means connected to the pinion 103.

What I claim is:

1. A giant umbrella comprising a stem, supporting means for holding said stem in a substantially upright position, ribs pivotally carried by said stem, a sleeve slidable on said stem, bracing members connected to said ribs and said sleeve, means for moving said sleeve lengthwise of said 70 75 80 85 90 95 100 105 110 115 120 125 130 135 140 145 150 155 160 165 170 175 180 185 190 195 200 205 210 stem, means for locking said sleeve relative to said stem and, means engaging said stem and said bracing members outwardly of the inner ends thereof for holding said bracing members 5 against horizontal swinging movement.

2. A giant umbrella comprising a stem, supporting means for holding said stem in a substantially upright position, ribs pivotally carried by said stem, a sleeve slidable on said stem, bracing members connected to said ribs and said sleeve, means for moving said sleeve lengthwise of said stem, means for locking said sleeve relative to said stem, means engaging said stem and said bracing members outwardly of the inner ends 10 thereof for holding said bracing members against horizontal swinging movement, a flexible cover, means securing the cover to said ribs, and means engaging the cover and disposed about the stem for holding the central portion of the cover taut 15 when the umbrella is extended while permitting relative movement between the cover and the stem during the collapsing thereof.

3. In an umbrella having a stem and extensible ribs, a cover comprising a flexible member, a pocket for each rib fixed to the underside of the cover, said pocket including a pair of wall members, grommets in said wall members, and lacing engaging through said grommets for holding said wall members in closed position about said 25 ribs.

4. In an umbrella having a stem and extensible ribs, a cover comprising a flexible member, a pocket for each rib fixed to the underside of the cover, said pocket including a pair of wall members, grommets in said wall members, and lacing engaging through said grommets for holding said wall members in closed position about said 30 ribs, the outer ends of said pockets being closed and said ribs abutting at their outer ends against the closed ends of said pockets to thereby tighten the cover on said ribs.

5. A giant umbrella comprising a stem, extensible ribs carried by said stem, bracing means for extending or collapsing said ribs, and means fixed 45 to said stem and to certain of said bracing means outwardly of the inner ends thereof for holding said bracing means against swinging movement relative to said stem.

6. A giant umbrella comprising a stem including a lower stem member, an upper stem member, a base for said lower stem member, means rotatably mounting said upper stem member on said lower stem member, means for rotating said upper stem member, a plurality of radial ribs, 50 means securing said ribs to said upper stem member, means for extending or collapsing said ribs, and collapsible means connected to said upper stem member and certain of said ribs for holding said ribs against swinging movement relative to 55 said upper stem member.

7. A giant umbrella comprising a lower stem member, an upper stem member, means rotatably mounting said upper stem member on said lower stem member, a plurality of radial ribs, 60 means pivotally securing the inner ends of said ribs to said upper stem member, means for extending or collapsing said ribs, a base, means for rockably mounting said lower stem member on said base, means carried by said base and engaging 65 the lower end of said lower stem member for tilting said stem members, and means extending

through said mounting means and said lower stem member for rotating said upper stem member in its adjusted position relative to the vertical.

8. A giant umbrella comprising a stem, a plurality of ribs pivotally secured to said stem, means for extending or collapsing said ribs, a flexible bracing member secured at the opposite ends thereof to certain of said ribs, the intermediate portion of said flexible member being 10 wound about said stem, and means fixedly securing said intermediate portion of said flexible member to said stem.

9. A giant umbrella comprising a stem including a lower stationary stem member and an upper 15 rotatable stem member, a plurality of ribs, means pivotally securing said ribs to said stem, means for extending or collapsing said ribs, a base member including a pair of upstanding bearing members, a shaft journalled in said bearing members and engaging said lower stem member for pivotally securing the lower end of said stem to said base member, means carried by said base member and engaging said lower stem member below said shaft for tilting said stem, and means fixed to said upper stem member and extending through said lower stem member operatively connected to said shaft for rotating said upper stem member. 20

10. A giant umbrella comprising a stem, extendible ribs carried by said stem, each of said ribs comprising a longitudinally bowed substantially rigid member, truss means carried by each rib between the ends thereof, a sleeve slidable 25 on said stem, and extendible means pivotally connected to said sleeve and said truss means for holding said ribs in either extended or collapsed position.

11. A giant umbrella comprising a stem, a sleeve slidable on said stem, a cap fixed to said stem, a plurality of radially arranged longitudinally bowed and substantially rigid ribs pivotally secured to said cap, a pair of truss bars fixed to each rib intermediate the ends thereof and one on each lateral side thereof, a bracing 40 member fixed to each truss bar and to the rib, and extendible means pivoted to said sleeve and pivotally engaging between each pair of said truss bars for holding said ribs in either extended or collapsed position. 50

12. A giant umbrella comprising a stem including a lower stationary stem member, an upper rotatable stem member, and a reduced cylindrical part fixed to said upper stem member, depending from said upper stem member 55 and rotatably engaging within the upper portion of said lower stem member, a plurality of radially arranged ribs pivotally carried by said upper stem member, means for extending or collapsing said ribs, a base member including a pair of bearing 60 members, a drive shaft journalled in said bearing members and loosely engaging through said lower stem member upwardly from the lower end thereof, means carried by said base member and engaging said lower stem member below said shaft for tilting said stem, and means fixed relative to said upper stem member and extending axially of said lower stem member operatively connected to said shaft for rotating said upper stem member. 65

70 HERBERT G. PECK.
